W. J. BOUSQUET,
FLOAT CONTROLLED CIRCUIT CLOSER,
APPLICATION FILED APR. 11, 1917.

1,282,178.

Patented Oct. 22, 1918.

UNITED STATES PATENT OFFICE.

WILFRID J. BOUSQUET, OF WOONSOCKET, RHODE ISLAND.

FLOAT-CONTROLLED CIRCUIT-CLOSER.

1,282,178.

Specification of Letters Patent. Patented Oct. 22, 1918.

Application filed April 11, 1917. Serial No. 161,368.

To all whom it may concern:

Be it known that I, WILFRID J. BOUSQUET, a citizen of the United States, residing at Woonsocket, in the county of Providence and State of Rhode Island, have invented new and useful Improvements in Float-Controlled Circuit-Closers, of which the following is a specification.

My present invention pertains to a float controlled circuit closer, designed more particularly for use in refrigerator alarms, and consists in the peculiar construction, novel combinations and adaptation of parts hereinafter described and definitely claimed.

15 In the accompanying drawings which are hereby made a part hereof:

Figure 1 is an elevation showing a refrigerator or analogous device equipped with my novel circuit closer.

20 Fig. 2 is a vertical section taken in the plane indicated by the line 2—2 of Fig. 1, looking toward the left.

Similar numerals of reference designate corresponding parts in all of the views of 25 the drawings.

Similar numerals of reference designate corresponding parts in all of the views of 30 the drawings.

The refrigerator 1 is shown by way of example, it being manifest that my improved circuit closer is adapted to be used in combination with any device in which ice is used, with a view to warning a house wife or servant of the fact that the drip pan 9 of the refrigerator, ice chest or other device requires emptying.

In the present and preferred embodiment 35 of the invention, my novel mechanism comprises a vertically-movable rod 2, movable in a guide 3 on the refrigerator and provided with a terminal 10, and also with a bifurcated upper end 11, a hand lever 12, fulcrumed at 13 on a bracket 14 and having one of its ends disposed in the bifurcation and also having a hand grasp at its opposite end, a float 8 disposed in the water in the pan 9, a lever 5 suitably connected with the float 40 and fulcrumed at 6 in a pendent bracket 7 on the refrigerator, and a terminal 16 electrically insulated from the rod 2 and arranged in a normally open electric circuit with a source of electric energy 15, a bell or 45 other audible or visual signal 17 and the rod 2. When desired a switch 18 may be included in the circuit referred to, but the said switch is not necessary to the successful operation of my invention, and therefore it 50 may be omitted when desired. I would also have it understood that without affecting my

invention the battery 15 and the signal 17 may be arranged at any points preferred by the party practising my invention.

With the parts arranged as shown, and the circuit closed or completed through the switch 18, it will be manifest that when the float 8 is raised by unduly high water in the pan 9, the terminal 10 will be lowered into contact with the terminal 16, whereupon the circuit will be closed and the signal 17 actuated to apprise a person in authority of the necessity of emptying the pan.

When it is desired to remove the pan precedent to emptying the same, it is simply necessary for the operator to raise the outer end of the lever 12 and depress the rod 2 sufficiently to raise the float 8 clear of the pan 9 so that the said float will not interfere with the movement of the pan away from and into the position illustrated. It will be manifest in this connection that the terminal 10 is adapted to wipe past the terminal 16, and consequently the illustrated relative arrangement of the said terminals will not prevent or interfere with the described manual depression of the rod 2.

It will be gathered from the foregoing that my novel mechanism is reliable in operation, is adapted to be readily installed and is made up of parts which are adapted to withstand the rough usage to which devices of corresponding character are ordinarily subjected.

The means shown and described for closing the electric circuit and actuating the signal when the rod 2 is lowered is preferred because of its simplicity and inexpensiveness, but I desire it distinctly understood that my invention is not limited to the said means or any other specific means for completing the circuit incidental to downward movement of rod 2.

The term "terminal" as herein employed is intended to comprehend a contact of any description.

Having described my invention, what I claim and desire to secure by Letters-Patent, is:

1. A float controlled circuit closer, comprising a float, a vertically-movable lever connected with the float, a terminal, a vertically-movable rod adapted to be arranged in a normally open circuit with a source of electric energy and the terminal and having a terminal adapted to coöperate with the first-named terminal; said rod being con-

nected with the opposite end of the lever, with reference to the float, a pan in which the float is located, and means constructed and arranged for the convenient manual de- 5 pression of the rod to raise the float clear of the pan.

2. In means for the purpose described, the combination of supporting means, a vertically-swinging lever fulcrumed at an intermediate point of its length on the supporting means, a float carried on one arm of said lever and adapted to be disposed in a pan arranged under and removable edgewise from below the supporting means, a vertically-movable rod guided on said supporting

means to control an electric circuit and connected with the other arm of said lever, and a hand lever fulcrumed at an intermediate point of its length on the supporting means and having an outer handle portion and also 20 having an inner portion constructed and arranged on downward movement thereof to move the rod downwardly.

In testimony whereof I have hereunto set my hand in presence of two subscribing 25 witnesses.

WILFRID J. BOUSQUET.

Witnesses:

ALCIDE CHOQUETTE,
EDGAR L. SPAULDING.
